AIR IMPELLER

Filed Dec. 6, 1940

UNITED STATES PATENT OFFICE

2,309,351

AIR IMPELLER

William A. Norris, Alhambra, Calif.

Application December 6, 1940, Serial No. 368,796

3 Claims. (Cl. 170—159)

This invention relates to improvements in air impellers.

The general object of my invention is to provide an improved air impeller adapted for use either free or in a conduit.

Another object of the invention is to provide an air impeller device including novel means for controlling the air stream therefrom.

A further object of the invention is to provide an air impeller device including novel means to accumulate air adjacent to the axis thereof.

A still further object of the invention is to provide an air impeller device including a novel leading edge.

An additional object of my invention is to provide an air impeller including a novel scoop.

Other objects and the advantages of this invention will be apparent from the following description taken in connection with the accompanying drawing wherein:

Fig. 1 is a cross-section through a conduit showing my improved air impeller device operatively mounted therein;

Fig. 2 is a fragmentary longitudinal section through a conduit showing a side elevation of my improved impeller device;

Fig. 2A is a sectional view taken on line 2A—2A Fig. 1;

Fig. 2B is a sectional view taken on line 2B—2B Fig. 1;

Fig. 3 is a side elevation of a modified form of the device shown in Fig. 1;

Fig. 4 is a side elevation of a still further modified form of the device shown in Fig. 1;

Fig. 5 is a face view of an airplane type air impeller including the features of my invention;

Fig. 6 is a side elevation of the device shown in Fig. 5; and

Fig. 7 is a section taken in line 7—7, Fig. 6.

Referring to the drawing by reference characters, I have indicated my improvement in impeller device generally at 10. As shown, the device 10 includes a plurality of spaced blades 12 mounted on a base member 13.

Each of the blades 12 comprises a leading edge portion 14, which is at the inlet end of the device. From the leading edge 14 the blade is inclined forwardly as at 15 to form a propelling surface. The portion of each blade nearer its axis for a predetermined distance forwardly curves rearwardly as at 16 and then extends parallel as at 17 to the plane of the leading edges 14 to form a scoop portion 18.

The base member 13 includes a plurality of

spaced radially extending arms 19. Each arm has one of the blades 12 received thereto as by welding.

The base 13 is adapted to be mounted on the armature shaft 20 of an electric motor 21 which in the drawing is shown as supported within a conduit 22 by a suitable bracket 23.

In operation when the motor 21 is operating it drives the impeller device in the direction indicated by the arrow in Fig. 1. As the impeller rotates the leading straight edge portions 14 cleaves the air without making the usual noise which is produced when the air is cleaved with an angularly disposed surface. The scoop portion 18 of the blades picks up and compacts air at the center of the device and centrifugal force moves the air outwardly where the driving surface 15 forces it forward. Thus a heavy column of air is delivered from the impeller.

20 In Fig. 3 I have indicated a modified form of impeller device generally at 25. As shown the device 25 is similar in all respects to the impeller device 10 except that it is shown as having only four blades and the blades are inclined forwardly and outwardly from the axis thereof. In Fig. 3 like portions are indicated by similarly primed reference numerals.

25 In Fig. 4 I have indicated a further modified form of impeller device generally at 26 and have indicated like portions thereof by similarly double primed reference numerals. The device 26 is similar in all respects to the device 10 except that it is shown as only having four blades which are inclined rearwardly and inwardly.

35 In Figs. 5, 6 and 7 I have shown my invention applied to a two blade airplane type impeller 30. As shown the device 30 includes a central hub portion 31 having a bore 32 therein for mounting it on a suitable drive shaft and a pair of opposed blade members 33. The body portion 34 of each of the blades is inclined at the desired angle and a portion 35 thereof at the leading edge is formed in a plane perpendicular to the axis of rotation.

40 Extending outwardly from the hub 31 a predetermined distance a portion of the trailing edge of each blade curves forwardly at 36 (Fig. 7) and includes a forwardly extending portion 37 which forms a scoop portion 38 similar to the scoop portion 18 of the blades 12 of the device 10. The device 30 functions in substantially the same manner as previously described in connection with the device 10.

50 From the foregoing description it will be apparent that I have provided a novel air impeller

which is simple in construction and highly efficient in use.

Having thus described my invention I claim:

1. In an air impeller, a hub, a plurality of radially disposed blades, each of said blades including an elongated body having a substantially straight leading edge disposed at the inlet edge of the blade, each blade from the leading edge being inclined to form an air propelling surface, the portion of each blade nearest the axis thereof having a short extending portion which terminates in an edge portion which is spaced from the leading edge to form a scoop portion, the scoop portion having an unobstructed entrance, the end of each blade nearest the axis and at the free edge of the scoop portion being free from attachment to the hub, each blade being secured to the hub along a substantially radial line, the leading edge of each blade being parallel to and in advance of the substantially radial line along which the blade is secured to the hub.

2. In an air impeller, a hub, a plurality of radially disposed blades, each of said blades including an elongated body having a substantially straight and flat leading edge disposed at the inlet edge of the blade, each blade from the leading edge being inclined to form a propelling surface, the portion of each blade nearest the axis thereof having a short rearwardly extending portion which terminates in an edge portion which is substantially planar and spaced from the leading edge to form a scoop portion, the scoop por-

tion having an unobstructed entrance, the leading edge portion and the body of the blade adjacent the leading edge portion being free from attachment to the hub, each blade being secured to the hub along a substantially radial line, the leading edge of each blade being parallel to and in advance of the substantially radial line along which the blade is secured to the hub.

3. In an air impeller, a hub, a plurality of radially disposed blades, each of said blades including an elongated body having a substantially straight and flat leading edge disposed at the inlet edge of the blade, each blade from the leading edge being inclined to form a propelling surface, the portion of each blade nearest the axis thereof having a short rearwardly extending portion which terminates in an edge portion which is substantially planar, spaced from, and disposed forward of, the leading edge to form a scoop portion, the scoop portion having an unobstructed entrance, the inner and outer ends of each blade being parallel and perpendicular to the plane of its flat leading edge, the leading edge portion and the body of the blade adjacent the leading edge portion being free from attachment to the hub, each blade being secured to the hub along a substantially radial line, the leading edge of each blade being parallel to and in advance of the substantially radial line along which the blade is secured to the hub.

WILLIAM A. NORRIS.
